1,547,313

July 28, 1925.

C. B. FOSTER

CARD GAME

Filed April 19, 1923

2 Sheets-Sheet 1

Fig. 3.

Fly to Left	Foul Fly to C	Foul Fly to 1st	Foul Fly to 3rd	Foul Fly to Rig	Foul Fly to Left	Foul Fly to LEFT
FLY 1	FOUL 2C	FOUL 1ST	FOUL 3RD	FOUL 4TH	FOUL FLY TO LEFT	FOUL FLY TO LEFT

INVENTOR.
Clarence B. Foster
BY Lyon & Lyon
ATTORNEYS

1,547,313

July 28, 1925.

C. B. FOSTER

CARD GAME

Filed April 19, 1923

2 Sheets-Sheet 2

Fig. 4.

Fig. 6.

Fig. 7.

Fig. 5.

INVENTOR.
Clarence B. Foster
BY
Lyons & Lyons
ATTORNEYS

Patented July 28, 1925.

1,547,313

UNITED STATES PATENT OFFICE.

CLARENCE B. FOSTER, OF GLENDALE, CALIFORNIA, ASSIGNOR OF ONE-TENTH TO LEONARD S. LYON, OF LOS ANGELES, CALIFORNIA.

CARD GAME.

Application filed April 19, 1923. Serial No. 633,058.

To all whom it may concern:

Be it known that I, CLARENCE B. FOSTER, a citizen of the United States, residing at Glendale, in the county of Los Angeles and 5 State of California, have invented a new and useful Card Game, of which the following is a specification.

This invention relates to card games, and is particularly directed to a card game based 10 upon the science and method of play of base-ball.

It is an object of the invention to provide a card game by which the various plays of base-ball may be represented in detail and 15 in faithful conformity with nationally recognized methods of the playing of base-ball, and in the playing of which the players may fully utilize their knowledge of the science and strategy of base-ball.

20 Another object is to provide a card game in the playing of which the baseball knowledge of the players is the major element of success, and in which the element of chance has been reduced to a minimum.

25 Another object is to provide a card game by which offense and defense plays are represented in detail and are at all times fully under control of the respective players.

30 A further object is to provide a card game in which an umpire element has the same controlling relation as does an umpire in the field game of baseball.

35 Another object is to provide a card game in which a card is played for each fielder handling the ball in a defense play, and in which the value of the defense play is determined by the umpire element.

40 It is a further object of the invention to provide a card game including a representation of a baseball playing field, and a plurality of elements representing base runners, and in which said base runners are at all times controlled by the offense player, and are advanced on subsequent plays in 45 accordance to the control thereof previously exercised by the offense player.

45 Another object is to provide a game in the playing of which, every detail of play is formulated in the minds of the respective players and a card played for each detail of a play.

50 Still another object is to provide a card game in which the success of the players largely depends upon their knowledge of the "official" rules of baseball.

55 A further object is to provide a card game which so faithfully represents the various and intricate plays of baseball as to be fully adapted for use in the teaching of "inside baseball" or the conducting of what is known as "skull-practice."

Various other objects and advantages will be more fully apparent from the following description of the accompanying drawings which form a part of this disclosure, and 65 which illustrate a preferred form of embodiment of the invention.

Of the drawings:

Figure 1 illustrates the various defense cards.

Fig. 2 illustrates the various umpire cards.

Fig. 3 illustrates the various offense cards. Fig. 4 is a plan view of a game board representing a baseball playing field.

Fig. 5 is a view showing one of the elements representing a base runner, and adapted to be manipulated upon the game board by the offense player.

Figs. 6 and 7 illustrate modified forms of "umpire" elements.

The basic idea underlying the card game of the present invention is to so closely adhere to the modern accepted science and strategy of the national game of baseball and the "official rules of baseball", and to so represent the details of play step-by-step, that the game is fully adapted for the teaching of the mental elements of base ball, such mental study of the science of "inside" baseball being a form of that phase of baseball generally referred to as "skull-practice."

To be of any particular use or value in this direction it is of major importance that the mentality of the players as regards to their knowledge of the intricate problems of base ball, be given full and unrestricted scope in working out the minute details of play, and that such details of play be individually represented as independent units of the game to be combined into complete plays by the players according to their individual conceptions and desires, such freedom of play being limited only by the fixed rules of the game and by the players' knowledge of baseball science.

Referring particularly to Fig. 1 of the drawings, there is illustrated a plurality of ten different "defense" cards, a complete pack of such "defense" cards preferably including six of the "catcher" cards 10, three 110 of the "pitcher" cards 11, twelve of the "first-base" cards 12, seven of the "second-base" cards 13, seven of the "third-base" cards 14, seven of the "short stop" cards 15, five of the "left-field" cards 16, five of the "right field" cards 17, five of the "center-field" cards 18, and three of the "strike-out" cards 19.

In Fig. 2 I have illustrated two different "umpire" cards, a complete pack of such cards preferably including five "safe" 10 umpire cards 20, and twenty "out" 11 umpire cards 21, it being understood that this ratio may be variously modified so as to either "tighten up the game" or increase the 12 chances of scoring.

Fig. 3 illustrates a plurality of different "offense" cards, a complete pack of such cards preferably including, one "home-run" 15 card 22, two "walk" cards 23, three "bunt" 16 cards 24, one "wild-throw" card 25, one 20 "wild-pitch" card 26, two "error" cards 27, two "steal" cards 28, one "balk" card 29, six each of the grounder cards 30, 31, 32, 33, 34, 35, 36, 37, 38, 39, 40, one each of the fly cards 41, 42, 43, 44, 45, two each of the fly cards 46, 47, 48, and one each of the foul-fly cards 49, 50, 51, 52, 53.

Fig. 4 illustrates a game board representing a base-ball field, and which in addition 30 to an illustration of the regulation base-ball diamond, has three "lead-spots" 54, 55, 56, spaced forwardly along the base lines a short distance from the respective bases.

Fig. 5 illustrates a scoring element 57, of 35 which there may be several, and which is adapted to be manipulated upon the game board to represent a base runner, it of course being evident that any object of suitable size 40 may be used as a scoring element, and that the element shown in the drawings is only one of a preferred form.

In Fig. 6 I have shown a modified form of "umpire" element, which consists of a spin 45 wheel device having its base 58 marked to designate "out" and "safe" decisions, and a pointer 59 adapted to be spun and to indicate a decision upon stopping.

In Fig. 7 I have illustrated another modified form of "umpire" element, consisting 50 of a dice having one face 60 marked "safe" indicating a "safe" umpire decision, and with the other five faces 61 marked "out" indicating "out" umpire decisions.

It is believed that the following rules, and 55 the example of play which includes in four innings the majority of the different possible plays, will so fully describe the method of conducting the game that no other description or discussion will be necessary for a complete understanding of this game, by those skilled in the art of baseball.

RULES.

1. The game is played by two players representing opposing baseball teams,

2. All plays are made exactly as in baseball, and no plays should be attempted which are not possible in baseball.

3. The official rules of baseball shall govern all plays and scoring of the game.

4. No card can be recovered after it is played.

5. At the start of the game the players shall determine which shall be first at bat, the team at bat being the "offense" and the 75 team in the field the "defense", the players alternating as "offense" and "defense" throughout the game.

6. The "offense" plays with the "offense" 80 cards and the "defense" plays with the "defense" cards, the "umpire" cards being turned by the "offense" player.

7. The field board is always turned so the home plate is directly in front of "offense" 85 player.

8. At the start of each half inning, each player shuffles opponent's cards and deals him nine cards, placing the remainder of the pack face down at opponent's right.

9. "Defense" shuffles "umpire" cards and 90 places them, face down, near first-base.

10. As each player plays a card, he places it face up in front of him, at the same time calling his play.

11. At the start of each half inning and 95 also after every completed play, "offense" cannot play until "defense" passes, and in each case "defense" may play first only if he can play a "strike-out" card. If he has no "strike-out" card or does not care to play one, he passes, and then "offense" may play. The exception to this rule is that, with a runner on, "offense" may play a "balk" or "wild-pitch" card before "defense" plays, to 105 advance runner one base, but a "balk" or "wild-pitch" does not send batter to first.

12. When "offense" plays "balk", "wild-pitch", or "walk", no defense play is possible, and "defense" can discard one card 110 and draw one card to better his hand, as under rule 15. "Offense" should not play "balk" or "wild-pitch" with no runners on, as this would be a "bone-head" play, but if he does he cannot take such card back into 115 his hand.

13. A "wild-throw" card should be played only following a thrown ball play by "defense", and if played at any other time it is 120 a "bone-head" play and "offense" cannot take such card back into his hand.

14. After each play is completed by both players, the ball is considered to be in pitcher's possession, and each player draws from the top of his own pack as many cards 125 as he used in making the play, so that at the start of each play he holds a full hand of nine cards.

15. After any completed play in which a player was unable to play at least one card, 130 such player may discard one card and draw one card from his own pack to better his hand.

16. In making a defensive play, "defense" must play a proper card for each fielder handling the ball, and "offense" must turn an "umpire" card for every decision required, as the play is executed.

17. As "offense" plays, he moves his runners around the bases, stopping them 10 at the proper bases as he completes each play.

18. "Offense" can advance any runner to the nearest "lead-spot" or return any runner from "lead-spot" to his base at any 15 time between the completion of one play and the beginning of the next play.

19. Runners holding their bases are advanced one, two, or three bases on a single, double, or triple.

20. Runners on "lead-spots" are advanced two bases on a single not due to an error or to dropping of fly or line-drive, and three bases on a double not due to an error or to dropping of fly or line-drive.

21. Runners on "lead-spots" are subject to being caught off base at any time before ball is hit, by a "defense" play pitcher or catcher to first, second or third base, or to short-stop playing second, after which an 30 "umpire" card is turned for a decision at the base played to.

22. "Offense" must at all times definitely control his runners by announcing the movements of each and also by moving his men 25 on the field board, otherwise all runners are considered as taking no lead off bases and as running as soon as ball is hit.

23. All runners are considered as stopping at bases to which safe hit entitles them, 40 unless sent further by "offense" player at risk of being put out.

24. If "offense" starts a runner from a base at which baseman has the ball, "defense" may announce "baseman tags runner" and an "umpire" card must then be turned for decision on the play.

25. When playing fly or line-drive card and before "defense" play is started, "offense" must announce "runners hold bases", otherwise "defense" may, after the ball is caught, play the ball to the base left by the runner, and such runner is automatically out for leaving his base too soon. But nothing will prevent "offense" allowing 55 runners to start as soon as ball is hit under liability of being put out, if he believes "defense" does not hold a proper card to stop the hit or if he believes the ball will drop safe. If "offense" holds runners on bases until ball is caught, he must then announce which runners try for next base after the catch, so that "defense" can make proper play on such runners. A "safe" 60 decision on such a play results in a sacrifice fly.

26. After "defense" starts a defensive play, "offense" cannot then announce that runners hold their bases.

27. "Infield fly". If before two men are out, while first and second, or first, second and third bases are occupied, "offense" plays a fly to infield card, "defense" may, after he plays a proper infielder card, call "infield fly", and batter is then automatically out, and, further, if "offense" has not 75 announced "runners hold bases" before start of "defense" play, "offense" must then turn an "umpire" card to determine whether fly is caught or is dropped. If fly is caught, "defense" will play the ball to a 80 base left by the runner, for an automatic out as in rule 25, and if the ball is dropped "defense" will play the ball to the next base, in which case another "umpire" card is then turned for a decision at such next 85 base.

28. Fielding of batted balls. When "offense" plays a grounder, line-drive, or fly card, "defense" must first play a fielder's card corresponding to the fielder to whom the ball is hit, to signify that the proper fielder is fielding the ball.

Section 1. On a grounder, such a play signifies that the fielder has fielded the ball cleanly, and "defense" then plays a card 95 corresponding to the baseman to whom the ball is thrown in making the play. For example; on "grounder to short", "defense" plays "short-stop" card and then 100 a "first-base" card, if the play is made to first, calling the play "short to first". "Offense" then turns "umpire" card for a decision on first. If the play is made to second, third, or home, on a fielder's choice, "defense" plays either "second-base", 105 "third-base", or "catcher" card, instead of "first-base" card, calling the play, "short to second", or "short to third", or "short to home", as the case may be.

Section 2. On a line-drive the playing of 110 a fielder's card corresponding to the fielder to whom the ball is hit, only signifies that such fielder stopped the ball, and an "umpire" card must then be turned before further play, to determine whether the drive was legally caught for an out or was only knocked down. An "out" umpire card signifies a fair catch for an out, and a "safe" 115 umpire card signifies that the ball was only knocked down by the fielder. A line-drive to the outfield which is not caught but which is knocked down, is good for a safe single, but a line-drive to the infield which is knocked down is not in itself a safe hit, but 120 must be played to a base for a decision, the same as in section 1 for grounders, because an infilder is considered as having ample time after knocking down a line-drive to make a play to a base to catch a runner.

Section 3. On a fly, the playing of a field- 130 er's card corresponding to the fielder to whom the ball is hit only signifies that such fielder has fielded the ball, and an "umpire" card must then be turned before further play, to determine whether the fly was legally caught for an out or was dropped. An "out" umpire card signifies a fair catch for an out, and a "safe" umpire card signifies that the fielder dropped the ball. An out-field fly falling safe is good for a safe double and an infield fly falling safe is good for a safe single, as a runner usually reaches a base before a fly to the infield which falls safe can be fielded to a base.

15 Section 4. When "defense" cannot play a fielder's card corresponding to the fielder to whom a grounder or line-drive is hit, he must pass, and the ball is considered too hot to handle and goes through for a safe-hit.

20 When "defense" cannot play a card corresponding to the fielder to whom a fly is hit, he must pass, and the ball is considered as going over such fielder's head for a safe hit. In either case the play ends, unless "offense"

25 attempts to send runners further than the safe value of the hit. In case "offense" does so attempt to stretch the hit "defense" can then make the play from a fielder who would ordinarily back up the hit to a base to which a runner is advancing, and an "umpire" card is then turned for a decision at such base. If on an attempt to stretch a hit, "defense" cannot play a proper fielder's card to start a play such fielder is considered as having 30 fumbled the ball until too late to make the play and runners are safe and no "umpire" card need be turned, but no hit can be stretched more than one base.

35 Section 5. Double and triple plays are executed the same as in base-ball, "defense" playing a card for each fielder handling the ball and an "umpire" card being turned for each fly or line-drive decision and for each base decision as the play is made.

40 29. Value and backing-up of safe hits.

Grounder or line-drive to first, going through is a safe single and is backed up by right or center. Grounder or line-drive to second, going through is a safe single and is backed up by center or right. Grounder or line-drive to short, going through is a safe single and is backed up by center or left. Grounder or line-drive to third, going through is a safe single and is backed up by left or center. Line-drive to right, going through is a safe double and is backed up by center. Line-drive to center, going through is a safe double and is backed up by right or left. Line-drive to left, going through is a safe double and is backed up by center.

45 Fly to first, going over is a safe "Texas leaguer" single and is fielded by right or by second, with short or pitcher playing second-base. Fly to second, going over is a safe

"Texas leaguer" single and is fielded by center, with short or pitcher playing second-base, or by short with pitcher playing second-base. Fly to short, going over is a safe "Texas leaguer" single and is fielded by left 70 or center. Fly to third, going over is a safe "Texas leaguer" single and is fielded by short or left with pitcher playing third-base. Fly to right, going over is a safe triple and is fielded by center. Fly to center, going over 75 is a safe triple and is fielded by right or left. Fly to left, going over is a safe triple and is fielded by center.

Line drives to infield not caught, but which are knocked down ("safe" umpire 80 card or "error" card), are not safe hits and must be played same as grounders.

Line drives to outfield not caught, but which are knocked down ("safe" umpire 85 card) are safe singles.

Fly to infield, dropped ("safe" umpire card) are safe singles.

Fly to outfield, dropped ("safe" umpire card), are safe doubles.

30. Fielding bunts.

Bunts are fielded by catcher, pitcher, first or third, excepting, with runner on third, catcher cannot field a bunt, as he must play home plate. When first fields a bunt, second can play first-base, with short taking care of second-base. When third fields a bunt, short takes care of third-base.

31. "Error" and "wild-throw" cards, their uses and what they signify:

"Error" and "wild-throw" cards are 100 automatic safe cards and prevent turning of "umpire" card, therefore, no play can be turned into a double or triple play after either of these cards has been played.

"Error" following a throw signifies that 105 the base-man dropped ball and runner is safe.

"Error" following a grounder denotes a fumble and runners are safe.

"Error" played immediately after fly or 110 line-drive card and before turning of "umpire" card denotes that fielder dropped fly or only knocked down line-drive, the same as would a "safe" umpire card.

With no runner on first or after two men are out, an "error" following a "strike-out" signifies that catcher dropped third strike, and "defense" play must then be "catcher to first", and an "umpire" card turned for a 120 decision on first-base.

On infield wild-throws runners advance an extra base but not on wild throws from the outfield.

32. Use of steal cards.

Offense must play one "steal" card for 125 each runner attempting to steal, and only runners on "lead spots" can attempt to steal.

All plays to block steals must start with 130 catcher and play to block steal of home is made only with a "catcher" card, which in this use signifies that catcher has the ball ready to tag runner.

33. Use of umpire cards:

5 An "umpire" card is turned for each decision on flys and line drives and for each base decision.

10 An "umpire" card is not a base decision when used to determine whether a fly or line-drive is caught or is dropped or only knocked down, an "out" umpire card signifying in this case that the fielder caught the ball for an out, and a "safe" umpire card signifying that the fly fell safe or the line-15 drive was knocked down.

15 An "umpire" card is turned after each part of a double or triple play.

20 34. A squeeze play is made with runner on third-base "lead" spot, by playing "steal" and "bunt" cards together, and runner is automatically safe at the plate.

EXAMPLE OF PLAY.

First inning.

25 First half—"Defense," being first to play, plays "strike-out." "Offense" plays "error", signifying that catcher dropped third strike, and "defense" then makes the play from 30 catcher to first by playing, first, a "catcher" card, and then a "1st" card, announcing the play "catcher to 1st." "Offense" turns "umpire" card for a decision at first base, the decision being "out." (If, instead of turning 35 an "umpire" card, "offense" played another "error" card, it would signify that the first-baseman dropped the throw and the runner would be automatically safe, and no "umpire" card need be turned. Or, if 40 "offense" played a "wild throw" card, runner would go to second, and no "umpire" card need be turned.) "Defense" draws three cards, and "offense" draws one card.

One down: None on:

45 "Defense," not having another "strike-out" card, must pass. "Offense" now plays "walk," for which there is no defense, and places man on first-base. This is a completed play, and "offense" draws one card to 50 fill his hand, and as "defense" could not play at least one card on the play, he may discard one card and draw one card to better his hand, if he chooses.— "Offense," wishing the runner to take a lead off first, moves him to the "lead" spot. "Defense" now has a chance to catch the 55 runner, and plays a "pitcher" card and then a "1st" card, announcing the play "pitcher to 1st." (This play could also be made 60 from "catcher" to "1st.") "Offense" turns "umpire" card for a decision on the play, it being an "out." "Defense" draws two cards, and "offense," not using a card in the play, may discard and draw one card.

65 Two down: None on:

"Defense," not having a "strike-out" card, passes. "Offense" plays "grounder to short." "Defense" now makes the play, by first playing a "short" card and then a "1st" card, and announcing the play, "short to 1st." "Offense" turns an "umpire" card, which is a "safe." "Offense" places a man on first-base. "Defense" draws two cards, and "offense" draws one card.—"Defense," still not having a "strike-out" card, passes. "Offense" plays "grounder to 3rd." "Defense" plays a "3rd" card, then a "1st" card, announcing the play "third to first." (If "defense" did not have a "1st" card to complete this play, he could have used a "2nd" card for a play "third to second", or a "short" card for a play "third to short on second," either play being a force at second on a fielder's choice.) "Offense" turns "umpire" card, which is an "out".

80 Three down: No runs: One hit: One error:

Second half—"Defense" passes. "Offense" plays, grounder to first." "Defense" plays "1st" card, announcing "first touching first." (He could have played "1st" card, then a "pitcher" card, for the play "first to pitcher on first," if he wanted to use more cards so as to be able to draw more to better his hand.) "Offense" turns "umpire", which is a "safe." "Offense" places man on first and draws one card, and "Defense" draws one card.—"Defense" plays "strike out", and as first base is occupied, "offense" should not play "error", as batter cannot run on dropped third strike. "Defense" draws one card, and "offense," not having used at least one card in the play, discards and draws one card.

85 One down: Runner on first:

"Offense" moves runner to "lead" spot, and "defense", having no "strike out" card and not having proper cards to catch runner off base, passes. "Offense" plays "grounder to short". "Defense" plays "short" and then "2nd" and then "1st" cards, for an attempted double play, announcing the play "short to second to first." "Offense" turns two "umpire" cards, the first being an "out" decision on second-base and the second being an "out" decision on first-base. (If "defense" had no "2nd" card he could have used only his "short" card for the first half of the double play, by announcing "short touch second".)

100 105 Three Down: No runs: One hit: No errors:

Second inning.

First half—"Defense" passes. "Offense" plays "bunt" "defense" plays "pitcher" card and then "1st" card, announcing the play "pitcher to first." ("Defense" could have fielded the bunt with "catcher" or "3rd" card.) "Offense," instead of turning an 110 115 120 125 130

- "umpire" card, plays an "error" card, which signifies that first-baseman dropped the throw, and runner is safe. "Offense" places man on first-base. "Defense" draws two 5 cards and "offense" draws two cards.— "Offense" moves runner to "lead" spot. "Defense" not having a "strike out" card to play, and not having proper cards to make a play to catch runner off base, passes.—
- 10 "Offense" plays "steal". "Defense" plays "catcher" card and then a "2nd" card, announcing the play "catcher to second." (If "defense" had no "2nd" card he could have used a "short" card for the play "catcher 15 to short on second"). "Offense" turns "umpire" card, which is a "safe". "Offense" moves runner to second and draws one card, and "defense" draws two cards.— "Defense" passes. "Offense" plays "grounder 20 to first". "Defense", having no "1st" card to stop the hit, announces "went through for a single." "Offense" advances runner from second to third (according to rule 19) and places another man on first, and wishing 25 to play safe, does not try to stretch the hit, and the ball is considered as having been returned to pitcher. (If the runner on second had been on the "lead" spot he would have scored on the hit, (according to rule 30 20.) "Offense" draws one card and "defense", not having used at least one card in the play, may discard and draw one card.— "Defense," having just drawn a "strike out" card, plays it. ("Offense" cannot play 35 an "error" here, as first base is occupied.) "Defense" draws one card, and "offense", not having used at least one card in the play, may discard and draw one card.
- One down: Runners on first and third: 40 "Defense" passes. "Offense" plays "fly to center" and announces "runners hold bases". "Defense" plays "center" card to signify that the center-fielder stops the ball. "Offense" turns "umpire" card, which is 45 an "out", signifying that the fly is legally caught for an out. "Offense" immediately announces "runners try to advance." (This gives "defense" two ways to complete a play,—center to second or center to catcher)
- 50 "defense" plays "catcher" card, announcing the play "center to catcher". "Offense" turns "umpire" card for decision at the plate, it being a "safe," the fly being scored as a "sacrifice hit", and the runner 55 on first goes to second. (On the above play "offense" could have played a safer game by announcing "runner on third tries for home," and this would have held runner on first, leaving "defense" only the above defensive play of center to catcher; or he could have announced "runner on first goes to second," and this would have held runner on third, leaving, only a play center to second or center to short on second for the "defense" to attempt.) "Defense" draws two cards 65 and "offense" draws one card.
- Two down: One run scored and man on second:
- "Defense" passes. "Offense" plays "line drive to right." "Defense" plays "right" 70 card to signify that the right fielder stops the ball. "Offense" turns "umpire" card, which is a "safe," signifying that right fielder only knocked down the drive, but did not catch it for an out. The hit is a 75 safe single. "Offense" places a man on first and moves his runner from second to third, and, wishing to stretch the hit, announces "stretch to a double." As right fielder has already knocked down the hit and 80 has the ball, "defense" completes the play to the plate by playing a "catcher" card, announcing the play "right to catcher." "Offense" turns "umpire" card which is an "out". (If "defense" did not have a 85 "catcher" card to complete this play, he could have made a play to second for the third out, but the run would have scored.)
- Three down: One run: Two hits: One sacrifice hit: One stolen base: One error: 90
- Second half*—"Defense" passes. "Offense" plays "walk", and places man on first. "Offense" draws one card, and "defense" may discard and draw one card.— "Defense" 95 passes. "Offense" plays "balk" and advances runner to second. "Offense" draws one card, and "defense" may discard and draw one card.— "Defense" passes. "Offense" plays "grounder to third," and, to guard against a double-play, announces 100 "man holds second". "Defense" plays "3rd" card to stop the hit, but, having no "1st" card to complete the play, announces "safe," signifying that third baseman could not field the ball in time to make the play. 105 The hit is a safe single, and "offense" places man on first. "Defense" draws one card, and "offense" draws one card.— "Defense" passes. "Offense" plays "fly to second", and announces "runners hold bases". "Defense" 110 plays "2nd" card and announces "infield fly" (according to rule 27), and batter is automatically out. "Defense" draws one card and "offense" draws one card.
- One down: Runners on first and second: 115
- "Defense" passes. "Offense" plays "grounder to first". "Defense", having no "1st" card to stop the hit announces "through for a single". "Offense" advances runners to second and third and places man on first, and, wishing to stretch the hit, announces "stretch to double". "Defense" plays "right", who backs up first base (according to rule 29) and completes the play at the plate by playing a "catcher" 120 card. (The hit could have been backed up by "center" and the play made, center to catcher.) "Offense" turns "umpire" card, which is an "out", runner goes from second to third, and batter goes to second on the play. "Offense" draws one card and "defense" draws two cards.

5 Two down: Runners on second and third: "Defense" passes. "Offense" plays fly to left". "Defense" plays "left" card and "offense" turns "umpire" card, which is an "out", signifying that the fly is legally caught for the third out.

Three down: No runs: Two hits: No errors:

Third inning.

15 First half—"Defense" passes. "Offense" plays "fly to third". "Defense", having no "3rd" card, passes, and the hit is considered as going over for a safe "Texas leaguer" single, and "offense", wishing to stretch the 20 hit, announces "stretch to double". "Defense" backs up the hit by playing a "left" card, and completes the play by playing a "2nd" card, announcing the play "left to second". "Offense" turns "umpire" card, 25 which is a "safe". "Offense" places man on second and draws one card, and "defense" draws two cards.—"Defense" passes. "Offense" plays "line drive to left", and having an "error" card in his hand, he does not 30 hold his man on second. "Defense" plays "left" card to stop the ball and "offense" plays his "error" card instead of turning an "umpire" card, this signifying that left-fielder dropped the ball and the runners are 35 safe on first and third. "Defense" draws one card and "offense" draws two cards.—"Defense" passes. "Offense" plays "grounder to second". "Defense" plays a "2nd" card for a force at second, and then 40 a "catcher" card for an attempted double play, announcing the play "second touch second to catcher." "Offense", instead of turning an "umpire" card for decision at the plate, plays "wild throw" card, the run 45 scoring and the batter going to second. "Defense" draws two cards and "offense" draws two cards.—

One down: Runner on second: One run scored.

50 "Defense" passes. "Offense" moves runner to "lead" spot "defense", not having "strike out" or proper cards to catch runner off second, passes. "Offense" plays "line drive to short", but neglects to first 55 return runner from "lead" spot to second base and to announce that runner holds base. "Defense" plays "short" card to stop the ball and "offense" turns "out" umpire card, signifying that the drive is caught for an 60 out. "Defense" now lays "2nd" card, announcing the play "Short to second" and runner is automatically out at second for leaving his base before the catch. The result is a double play. Defense draws two 65 cards and "offense" draws on card.

Three down: One run: One hit: One error: One wild throw:

70 Second half—"Defense" passes. "Offense" plays "grounder to first". "Defense", having no "1st" card to stop the ball, announces "through for a single". "Offense" announces "stretch to double." "Defense", not having either "right" or "center" to back up the hit, announces "through for a double", and the play ends and ball is considered as returned to pitcher. "Offense" places man on second and draws one card, and "Defense" may discard and draw one card.—"Defense" passes. "Offense" places runner on "lead" spot. "Defense" again 80 passes. "Offense" plays "line drive to first". "Defense", still not having "1st" card, announces, "through for a single", the ball now being considered as rolling to the outfield, runner scoring from second base 85 "lead" spot. "Defense" plays "right" card and then a "2nd" card, announcing the play "right to second". (He could have used a "center" card instead of "right" or a "short" card instead of "2nd" with short 90 playing second base.) "Offense" turns "umpire" card for an "out" decision on second.

One down: None on: and One run scored:

"Defense" passes. "Offense" plays "line drive to right". "Defense", not having 95 "right" card to stop the ball, announces, "through for a double", the ball now being considered as rolling past right fielder. "Offense" announces, "stretch to a triple". "Defense" backs up the hit by playing "center" card and completes play to third by 100 playing "3rd" card. "Offense" turns "umpire" card for an "out" decision at third. "Offense" draws one card and "defense" draws two cards.

105 Two down: None on:

"Defense" passes. "Offense" plays "fly to center". "Defense" having no "center" card, announces "over for a triple", the ball being considered as going over center-fielder's 110 head. "Offense" announces "stretch to a home run". "Defense" backs up the hit by playing a "left" card (or "right" card) and completes a play to the plate by playing a "catcher" card. "Offense" turns "umpire" 115 card, which is an "out".

Three down: One run: Four hits: No errors:

Fourth inning.

120 First half—"Defense" plays "strike out". "Offense" passes. "Defense" draws one card and "offense" discards and draws one card.

One Down:

"Defense" plays "strike out". "Offense" 125 passes. "Defense" draws one card and "offense" discards and draws one card.

Two down:

"Defense" plays "strike out". "Offense" 130 passes.

Three down: No hits: No errors:

Second half—"Defense" passes. "Offense" plays "fly to right." "Defense" having no "right" card, announces "over for a 5 triple". "Offense" announces "stretch to a home run". "Defense", not having a "center" card to back up the hit, announces "safe", and runner scores. Defense discards and draws one card and "offense" draws one 10 card—"Defense" passes. "Offense" plays "walk", for which there is no defense. "Offense" draws one card and "defense" discards and draws one card—"Defense" passes. "Offense" plays another "walk". 15 "Offense" draws one card and "defense" discards and draws one card—"Offense" advances both runners to "lead" spots. "Defense", having no "strike out" or proper cards to catch either runner off base, passes. 20 "Offense" plays two "steal" cards for an attempted double steal. "Defense" plays "catcher" card and then a "3rd" card. "Offense" turns "umpire" card for decision on third, which is "safe". (If "defense" did not 25 have a "3rd" card he could have used a "2nd" or "short" card for a play to second, the runner going to third being safe.) "Offense" advances runner on third to "lead" spot. "Defense", having no "strike out" card 30 or proper cards to catch runner off third, passes. "Offense" plays "steal" and "bunt" cards, announcing "squeeze play", "runner holds second". Run scores and "defense" plays "pitcher" (or "3rd") card and then 35 "1st" card, announcing the play "pitcher to first". "Offense" turns "umpire" card, which is a "safe"—Runners on first and second. "Defense" passes. "Offense" plays "line drive to short," but neglects to hold runners 40 on their bases. "Defense" plays "short" card to stop the ball and "offense" turns "out" umpire's card, signifying that drive was caught for an out. "Defense" plays "2nd" and then "1st" card, announcing the play 45 "short to second to first". Runners are automatically out at first and second for leaving their bases before the catch, as explained in rule 25. The result is a triple play.

Three down: Two runs: Two hits: Two 50 stolen bases: No errors.

One feature of importance which is to be noted is that each play must be constructed by the players in every detail and that the 55 several details must be combined by the players, guided only by their knowledge of baseball science and the official rules of baseball, so that the game is as far remote from the automat as is possible with inanimate objects.

Another feature worthy of specific mention, 60 is that the "offense" and "defense" cards represent action rather than net results, that is, the "defense" cards designate the handling of the ball by the respective "defense" fielders but do not in themselves designate 65 net results as each handling of the ball by a fielder is followed by the turning of an "umpire" card for a decision on the play, or may be followed by an "error" or "wild-throw" 70 card played by the "offense", before a net result is obtained. Also the "defense" "strike-out" card does not in itself give a net result as, depending upon the condition of the 75 game, it may be followed by an "error" card played by the "offense."

Likewise the hit-ball "offense" cards 30 to 53, inclusive, designate the hitting of the ball and the character of the hit, while the "bunt" cards 24 designate the bunting the ball, and the "steal" cards 28 designate only the attempt by a base-runner to steal.

It will be evident from the above that I have provided a card game by which it is possible to designate every detail of play of the game of baseball as such details are 85 formulated or determined by the players, and in the playing of which the players may fully utilize their knowledge of baseball science and strategy.

Further the card game of the present invention is fully adapted to the use of teaching the details of "inside baseball" without deviation from the accepted "official rules of 90 baseball."

While the form of the invention herein 95 illustrated and described is fully adapted to fulfil all of the objects primarily stated, it is to be understood that I do not wish to limit the invention in this regard, for it is susceptible of embodiment in various other 100 forms, all coming within the scope of the following claims.

I claim:

1. A baseball card game including a plurality of cards designating offense plays, and 105 a plurality of cards designating normally unrelated units of defense play.

2. A baseball card game including a plurality of cards designating offense plays, a 110 plurality of cards designating attempted defense plays, and means by which the net results of the completed plays are determined.

3. A base-ball card game including a plurality of cards designating the direction and 115 character of batted balls, and a plurality of cards designating individual units of completed defense plays.

4. A baseball card game including a plurality of cards designating the direction and 120 character of batted balls, a plurality of cards designating individual units of attempted defense plays, and means by which the net results of the completed plays are determined.

5. A baseball card game including a plurality of independent cards designating offense plays, and a plurality of independent cards designating individual units of de- 125 fense plays and adapted to be played in selective sequence in completing defense plays.

6. A baseball card game including a plurality of cards designating offense plays, and a plurality of cards designating individual manual manipulations of a ball in attempted defense plays, to be played in coordination with the manual manipulation of a ball in execution of completed defense plays.

7. A baseball card game including a plurality of offense cards, and a plurality of defense cards designating individual units of defense plays and adapted to be played singly and in selective sequence to designate the successive units of a completed defense play.

8. A baseball card game including a plurality of offense cards designating the direction and character of batted balls, a plurality of defense cards designating individual unrelated units of defense plays and adapted to be played singly and in selective sequence to designate the successive units of a completed defense play as formulated by the defense player, and means by which the net results of such completed plays are determined.

9. A baseball card game including a plurality of cards designating offense plays, and a plurality of cards designating incomplete defense plays and adapted to be played singly and in varying sequence to indicate the individual manual manipulations of a ball in the execution of completed defense plays.

10. A baseball card game including a plurality of cards designating offense plays, a plurality of cards designating individual units of defense plays, and means for rendering umpire decisions, each defense card being normally independent of the other defense cards and designating the handling of a ball by one defense ball player, and the several defense cards being adapted to be played in selective sequence to designate the successive steps in the execution of completed defense plays.

11. A baseball card game including offense cards, defense cards, and an umpire element, a game board bearing a representation of a baseball diamond, and elements representing base runners and adapted to be variously positioned upon the board during the progress of the game, the game board having a lead-spot spaced forwardly along the base line from each base.

12. In a base-ball card game, a game board bearing a representation of a baseball diamond and having a lead-spot spaced forwardly along the base-line from each base, elements representing base-runners and adapted to be variously positioned upon the game board during the progress of the game, and defense cards whereby a defense play upon a runner occupying a lead-spot may be made.

13. In a baseball card game, a game board bearing a representation of a baseball diamond, elements representing base-runners and adapted to be variously positioned on said board during the progress of the game, and cards designating various plays, the board having a lead-spot adjacent each base determining the advancement of a base-runner by reason of a subsequent safe hit.

Signed at Los Angeles, California, this 14th day of April, 1923.

CLARENCE B. FOSTER.